UNITED STATES PATENT OFFICE.

GEORGE W. RAWLINGS AND GEORGE M. LANAM, OF DAYTON, WASHINGTON.

DESIGN FOR AN INDICATOR.

49,444.

Specification for Design.

Patented July 25, 1916.

Application filed April 28, 1916. Serial No. 94,265. Term of patent 14 years.

To all whom it may concern:

Be it known that we, GEORGE W. RAWLINGS and GEORGE M. LANAM, citizens of the United States, residing at Dayton, in the county of Columbia and State of Washington, have invented a new, original, and ornamental Design for Indicators, of which the following is a specification, reference being had to the accompanying drawing, forming a part thereof.

The figure is a plan view of an indicator, showing our new design.

We claim:

The ornamental design for an indicator, as shown.

GEO. W. RAWLINGS.
GEORGE M. LANAM.

Witnesses:

HARDY E. HAMM,
J. ELLIOTT SLIMP.
